APPARATUS FOR IDENTIFYING FLUIDS PASSING THROUGH A FORMATION TESTING TOOL

Keith H. Miner, Newport Beach, Calif., assignor, by mesne assignments, to Dresser Industries, Inc., Dallas, Tex., a corporation of Delaware

Application January 3, 1956, Serial No. 557,093

15 Claims. (Cl. 324—2)

This invention relates in general to well testing and more particularly to a system for determining the character and quantity of fluids initially produced from a given zone in an earth borehole.

In the drilling or reworking of wells, particularly oil and gas wells, it is desirable to determine, at any chosen depth in the well borehole, and prior to permanent completion thereof, the kind of fluid which the penetrated formation at such depth is capable of producing. A number of variations of so-called formation testing or drill stem testing systems have been heretofore employed for the purpose of obtaining such information regarding the potential production possibilities of drilled earth formations. These systems employ for the most part the now well known method usually comprising the lowering into the well borehole of a string of drill pipe, tubing, or the like tubular member carrying adjacent the lowered end thereof a suitable packer device adapted to seal off the annular space between such tubular member and a selected portion of surrounding borehole wall, thereby to isolate a chosen portion of the earth borehole below such packer and thereby to place it in communication with the lower end of such tubular member. A valve device manipulatable from the top of the well borehole is usually associated with the packer or lower portion of the tubular member, which valve can be initially closed to permit the tubular member to be run into the borehole empty or at least at a pressure substantially lower than that of the surrounding fluid in the well borehole.

Upon the setting of the packer followed by the opening of such valve, fluid from the borehole below the packer may then enter the lower end of the tubular member, followed by fluid from the surrounding earth formations, and such fluid may then rise in the tubular member either to a level where pressure equilibrium is established between the fluid column in the tubular member and that of the formations surrounding the earth borehole below the packer, or if the formation pressure is sufficiently high, such pressure equilibrium may not be established and continuous flow out through the tubular member may result.

In either event, it is desirable to be able to determine the sequence of entrance and the character and approximate amounts of the different kinds of fluid thus initially entering the tubular member of the testing tool.

Since, when the testing device valve is opened, the fluid may enter the testing tool with considerable velocity which tends to mix the different kinds of entering fluid, and also in event subsequent sampling of the recovered fluid sample is attempted by withdrawing the tubular member and catching samples therefrom as the joints of such member are broken, as has been the usual practice heretofore, much difficulty is encountered in obtaining accurate or useful information as to the aforementioned different kinds and quantities of fluid entering the testing tool.

It is, therefore, an object of this invention to provide

2

an improved system for well borehole production testing.

It is another object of this invention to provide an improved system for identifying the different fluids entering a well borehole production testing tool.

It is still another object to furnish a system for more accurately determining the quantities of the several different kinds of fluids entering a borehole and a well borehole production testing tool.

It is a still further object of this invention to furnish 10 an improved well borehole production testing tool capable of furnishing more information relative to the identities, quantities and sequence of entrance of the several different kinds of fluid which may enter such tool from a well borehole under test.

The objects of this invention are attained, in brief, broadly by means of a testing system which comprises a drill stem, pipe, tubing, or the like hollow container or tubular member, adapted to be lowered or extended into a well borehole to be tested, such member carrying adjacent the lower end portion thereof, or other suitable portion thereof, a packer device for packing off the annular space between such member and the surrounding borehole wall, thus to isolate a portion of the borehole adjacent the packer from other portions of the borehole, and a valve device in said container or tubular member adapted to be initially closed while said member and packer are being lowered into place in said borehole to exclude entrance of fluid into said member, and capable of being opened to permit entrance of fluid from the said isolated portion of said borehole into the said member, said packer and valve being manipulatable from the top of the borehole, and means associated with said member, valve and packer for indicating, or making a record correlated with time, of the measure of the resistivities or conductivities of such of the several kinds of fluid as may flow into said tubular member following the opening of said valve.

These and other objects, advantages and features of novelty of the invention will be evident hereinafter.

In the accompanying drawing wherein a preferred embodiment and best mode contemplated for accomplishing this invention is illustrated:

Figure 1 is a longitudinal sectional view of the general assembly of the apparatus in position within a typical well borehole;

Figure 2 is a fragmentary longitudinal sectional view in detail of a portion of the apparatus taken on line 2—2 of Figure 1;

Figure 3 is a schematic diagram of the electrical circuit of the apparatus of Figure 2;

Figure 4 is a longitudinal sectional view of an alternative form of the apparatus of Figure 1;

Figure 5 is an illustration of one type of graphical record which may be made by the apparatus of the invention.

Referring first primarily to Figure 1, a typical well bore hole is shown at 10 having an upper section 11 of relatively large diameter and having a lower section 12 of a reduced diameter relative to the aforesaid upper section. At the juncture of the upper section 11 and the lower section 12 of the well borehole is formed a tapered seat 13 into which and against which a tapered packing element 14 of a packer device, hereinafter more fully described, is forced to form a fluid seal or pack-off therewith, thereby to isolate the upper section 11 from the lower section 12 of the well borehole.

The testing apparatus assembly, as shown in Figure 1, is lowered into the well bore upon a drill stem, drill pipe, tubing or the like hollow or tubular member 16 and comprises, in addition to the beforementioned tubular member, a valve 19 which has an upper rotatable valve element 18 and a lower stationary valve element 20, a tubu-

lar mandrel 21 integral with and extending downward from the lower valve element 20, and a perforated pipe or strainer 24 which is coupled to the lower end of the mandrel 21 by means of coupling 22, said perforated pipe or strainer extending into the lower section 12 of the borehole when the testing apparatus is seated in position in the borehole as illustrated in Figure 1. The upper valve element 18 and the lower valve element 20 of the valve 19 are rotatable relative to each other about the longitudinal axis of the tool to the limited extent permitted by the slot 26 in the valve element 18 and pin 28 in the valve element 20 as best shown in Figure 4. The valve elements 18 and 20 are rotatably secured together, end to end, by means of the longitudinal shaft 29 integral with and extending coaxially up from the lower valve element 20 through a central bore in the upper valve element 18, said shaft 29 being provided with a threaded upper end carrying a retainer nut 30.

The upper valve element 18 and the lower valve element 20 in the valve 19 are each provided with a pair of internal, longitudinally extending passages 31 and 32 respectively, which in the one extreme rotational position of the valve elements relative to one another permitted by the aforementioned slot and pin 26, 28 as shown in Figure 1, are in registry with each other, thereby completing a pair of fluid passages through the valve 19 from the lower end of the tubular member 16 to the central passage 33 of the mandrel 21, which in turn makes connection with the interior of the upper end portion of the perforated pipe 24. In the extreme opposite position of the upper valve element 18 relative to the lower valve element 20 of the valve 19 permitted by the slot and pin 26, 28 the valve passages 31 and 32 are out of registry with each other, thus closing off communication between the lower portion of the testing tool through mandrel passage 33 from that of the upper portion of the tool leading into the tubular member 16.

Thus it will be apparent that after the testing tool is lowered into the borehole upon the drill stem or tubular member 16 and the packing 14 is forced into sealing and frictional engagement with the seat 13, the lower valve element 20 will thereby be held stationary and the valve 19 may then be opened or closed as desired, by rotation of the upper element 18 of the valve by rotary manipulation of the tubular member 16 from the top of the well borehole.

Adjacent the upper end of the before-described testing tool and within the tubular member 16, as shown in Figure 1, is located a fluid tight pressure resistant housing 35 supported centrally within the tubular member 16 by means of a plurality of radially extending web members 36 and 37 attached to the upper and lower heads respectively of the housing 35 and which make supporting engagement with the inside surface of the bore of tubular member 36. The construction of the container 35 and the contents thereof are more fully described hereinafter in connection with Figure 2.

Referring now primarily to Figure 2, the housing 35 is provided, on at least a portion of the exterior surface thereof, with a coating or covering 38 of a suitable electrical insulating material such as rubber, neoprene, Bakelite or the like rubber-like or plastic material. Upon the exterior surface of insulating covering 38 is carried a pair of longitudinally spaced-apart annular electrodes 39 and 40. The annular electrodes 39 and 40 are electrically connected by means of conductors 41 and 42 respectively which pass through insulating bushings 47 and 48 located in the wall of the housing 35 to measuring apparatus contained within the housing hereinafter more fully described.

A portion of the interior surface of the tubular member 16, at a location opposite the aforementioned coating 38, is preferably, although not necessarily, covered with an insulating coating 44 which may be composed of material which is the same as, or similar to, that of the before-mentioned coating 37.

Contained within the housing 35 are resistance-measuring means comprising an ammeter 45, connected in series through conductor 43 with a suitable current supply means 46 which series circuit is in turn connected, by way of conductors 41 and 42, across electrodes 39 and 40, as illustrated diagrammatically in Figure 3. The current supply means 46 may comprise an electric battery to produce a suitable direct current, or preferably it may comprise a source of alternating current including a battery and a suitable inverter or switching means to produce an alternating current, or a periodically reversed directed current of suitable frequency to be applied across the electrodes 39 and 40.

The meter 45 is provided with a pen 49 which rests upon and is adapted to draw a graphical record upon a moving chart 51 of values representative of fluid resistivity or conductivity versus time as shown at 49. The chart 51 is adapted to be driven at a predetermined uniform rate in the direction indicated by the arrow, by means of a clock drive mechanism 52 or other suitable means for this purpose, as is well known in the art.

While the apparatus of the invention has been hereinbefore described, by way of illustration, as being used in combination with a so-called rat-hole type drill stem formation tester in an open well borehole, it is to be understood that the apparatus may also be adapted to make the same or similar tests in a cased borehole, and under such condition a similar testing tool employing a sleeve packer or a so-called hook-wall type packer or a plurality of such packers may be used. Such testing apparatus may also be combined with a gun perforator device in a manner which is the same as or similar to that illustrated in the Spencer Patent No. 2,092,337, to perforate such casing prior to making such test.

While in Figure 1 the instrument housing 35 is shown to be located within the tubular member 16 and above the valve 19, it may also be located below the valve 19 and within the perforated pipe or strainer 24, as illustrated in Figure 4.

In operation of the before-described apparatus of this invention, the valve 19 is initially closed. The apparatus is then lowered down through the well borehole and through such fluid as is present therein until the packing element 14 is brought to rest upon the tapered seat 13 of the formation and forced thereagainst by the weight of the tubular member 16 sufficient to seal off the upper section 10 of the borehole from the lower section 12. By thus maintaining the valve 19 closed the fluid present in the well will be prevented from entering the tubular member 16 and thus the tubular member 16 will be initially maintained empty of fluid.

If desired, however, a suitable quantity of fluid may be introduced into the tubular member 16, above valve 19, as it is lowered into the well borehole to act as a cushion against the incoming fluid during the initial stage of the testing operation following the opening of the valve 19, as hereinafter more fully described.

When the testing apparatus has thus been lowered into the well borehole in readiness for testing, the valve 19 is then opened by turning the tubular member 16 to the extent permitted by the slot and pin 26, 28 to bring the passages 31 and 32 in the valve elements 19 and 20 respectively into registry and communication with each other as shown in Figure 1. The fluid in the lower section of the borehole 12 surrounding the perforated pipe 24 and also the fluid in the formation adjacent thereto being of relatively high pressure with respect to the interior of the tubular member 16 then flows inward through the perforated pipe 24 through the passage 33 of the mandrel 21 and thence up through valve passages 32 and 31 into the interior of the tubular member 16. As the fluid thus entering the testing tool continues to flow it passes upward through the annular space between the instrument housing 35 and the interior walls of the tubular member 16 until the fluid column in the tubular

member 16 has risen thereabove to a height where the pressure head thereof is in equilibrium with the pressure of the formation surrounding the lower section 12 of the borehole, or in case the formation pressure is sufficiently high, such fluid column within the tubular member 16 may reach the top of the well and flowing production of the well may thus be attained and maintained for a period of time.

As the fluid thus permitted to enter the lower end of the tubular member 16 through the before-described testing tool passes through the before-mentioned annular space surrounding the instrument housing 35, it comes in electrical contact with the annular electrodes 39 and 40. Current may thus be permitted to flow through such fluid between the annular electrodes 39 and 40 and through conductors 41, 42 and 53, and through the meter 45, under the influence of the potential or current source 46. The deflection of the pen 48 of the meter 45 will thus be a measure of or a function of the resistance or conductivity of a certain volume of the fluid at any particular time flowing between the aforesaid annular electrodes 39 and 40. As a result of the uniform movement of the chart 51 a graph 50 is drawn upon the moving chart 51 which, as before stated is a measure of or a function of the resistivity or conductivity, with respect to time, of the fluid passing in contact with the electrodes 39 and 40.

Referring now primarily to Figure 5, in which the graphical record 50 plotted by the apparatus of Figure 2 is shown in enlarged detail upon the chart 51, the time interval zero—*a* corresponds to that during which the testing apparatus, having the arrangement shown in Figure 1, is lowered into the well borehole with the valve 19 closed. During this time interval, when employing the apparatus of Figure 1, the conductivity of the fluid in the annular space surrounding the electrodes 39 and 40 being for example air, is indicated as substantially zero.

During the interval of time *a*—*b* the valve 10 is in the process of being opened by rotation of the tubular member 16, and the time interval *b*—*c* represents that required for the entrance of the fluid contained in the borehole section 12 surrounding the perforated pipe 24 to pass upward through the testing tool and completely to fill the annular space in the tubular member 16 surrounding the instrument housing 35.

The time interval *c*—*d* is that during which the relatively low resistivity borehole fluid, which may be drilling mud, which had been entrapped in the lower section of the borehole 12 below the packing element 14 and surrounding the perforated pipe 24 is being displaced upward into the tubular member 16 and is flowing through the annular space surrounding the instrument housing 35 in contact with the electrodes 39 and 40, and the resistivity measurement maintained during such period *c*—*d* indicates the resistivity value of such borehole fluid.

The time interval *d*—*e* indicates the effect of the conductivity measurement during the transition from flow of fluid initially entrapped in the lower portion of the borehole surrounding the perforated pipe 24 to and inclusive of fluid from the surrounding formation which was present in such formation by reason of invasion or infiltration thereof from the borehole during drilling.

The time interval *e*—*f* represents the measure of the conductivity of the fluid flowing from the formation after substantially all of the invasion fluid has been displaced from the formations adjacent the point of test, and flow of substantially uncontaminated connate fluid from the surrounding formations has been established. In the case illustrated in Figure 5, since the conductivity of the connate fluid is indicated as being substantially lower than that of the borehole fluid and of the invasion fluid, this may be taken, for example, as an indication of the production of a relatively low conductivity fluid such as oil or gas during this time interval.

Upon completion of the foregoing steps in the testing

75

operation the valve 19 is closed by rotation of the valve element 18, the packer released and the tubular member 16, together with the testing tool, withdrawn from the borehole. The time interval *f*—*g* represents the time during which such withdrawal from the borehole is effected and during which the indicated conductivity of the retained fluid obviously remains constant.

With a known fluid column height established within the tubular member 16 upon the completion of the test, or in the case of continuous flow of known rate being established, then from the known time intervals of flow of the different kinds of fluid through the testing tool as indicated by the record of the type illustrated in Figure 5, the relative quantities of the various kinds of such fluid may be estimated.

Operation with the apparatus of Figure 4 will result in a record similar to that shown in Figure 5 except that because the instrument housing 35 and particularly the electrodes 39 and 40 are located below the valve 19 the fluid in the borehole can come into contact with the electrodes during the initial lowering of the apparatus into the well bore and before the valve 19 is opened. Therefore, in such casing the graph 50 may show an initial reading which represents the conductivity of such fluid present in the well bore during the initial time interval zero—*a*. Also during withdrawal of the apparatus from the well bore during interval *f*—*g* the electrodes may again be brought into contact with borehole fluid and the graph 50 may show an increase in conductivity during that interval. Otherwise the graph 50 will be of the same character whether made by the apparatus arrangement of Figure 1 or Figure 4.

An important feature of the present invention resides in being able to obtain an indication of the character and quantity of the different kinds of fluid as they enter the testing tool, regardless of the extent of subsequent intermixing of the different kinds of such fluids resulting from turbulence of flow which may occur within the drill stem or tubular member above the testing tool as the entering fluid rises therein. It also has the advantage over systems hereinbefore employed where the kinds and quantities of fluids recovered by the testing tool had to be determined by breaking the joints of the tubular member as it is withdrawn from the well and catching, as best as possible, the fluid discharged at such joints.

The arrangement of the apparatus illustrated in Figure 4 may be advantageous in some cases in permitting measurement of the resistivity of the various fluids entering the testing tool prior to passing through the tool and prior to such initial turbulence and mixing as may occur therein. The undesirable effect of mixing of the fluids will thus be minimized.

While one arrangement of electrodes adapted to make electrical contact with fluid entering the testing device is illustrated by way of example in Figures 2 and 3, other arrangements may be employed, within the skill of the art, to insure proper measurement of the desired electrical characteristics of such flowing fluids.

It is to be understood that the foregoing is illustrative only and that the invention is not to be limited thereby, but includes all modifications thereof within the scope of the invention as defined in the appended claims.

What is claimed is:

1. A method of testing the production of a well comprising: lowering into the bore of the well to be tested a tubular member initially closed against entrance thereto of fluid from said well bore; effecting a packoff between said tubular member and a portion of the wall of the well bore at a selected location within the well bore wall to isolate a portion of said well bore from other portions thereof; opening the said tubular member to allow fluid to enter said tubular member from the thus isolated portion of said well bore wall; and making a measure during entrance, indicative of the resistivity at a given

section thereof of the entire stream of fluids thus permitted to enter said tubular member.

2. A method of testing the production of a well comprising: lowering into the bore of the well to be tested a tubular member initially closed against entrance thereto of fluid from said well bore; effecting a packoff between said tubular member and a portion of the wall of the well bore at a selected location within the well bore to isolate a portion of said well bore from other portions thereof; opening the said tubular member to allow fluid to enter said tubular member from the thus isolated portion of said well bore; and making a measure with respect to time during entrance indicative of the resistivity at a fixed section thereof of the entire stream of fluids thus permitted to enter said tubular member.

3. A method for testing the production of a well comprising: lowering into the bore of the well to be tested a tubular member initially closed against entrance thereto of fluid in said well bore; effecting a packoff of the annular space between the said tubular member and the surrounding wall of the well bore at a selected point within said well bore to isolate a portion of said well bore from other portions thereof; opening the said tubular member to allow fluid to enter said tubular member from the thus isolated portion of said well bore; and making a measure at a fixed location therein indicative of the resistivity of the entire stream of said fluid thus permitted to enter said tubular member, said measure being made in correlation with time during such entrance of said fluid into said tubular member.

4. A method for testing the production of a well comprising: lowering into the bore of the well to be tested a tubular member initially closed against entrance thereto of fluid in said well bore; effecting a packoff of the annular space between the said tubular member and the surrounding wall of the well borehole at a selected point within said well bore to isolate a portion of said well bore from other portions thereof; opening the said tubular member to allow fluid to enter said tubular member from the thus isolated portion of said well bore; and at a location fixed with respect to said tubular member, making a measure indicative of the resistivity of the entire stream of said fluid passing said location as said fluid enters said tubular member, said measure being made in correlation with time during such entrance of said fluid into said tubular member.

5. A method for testing the production of a well comprising: lowering into the bore of the well to be tested a tubular member initially closed adjacent the lower end thereof; effecting a packoff of the annular space between the said tubular member and the surrounding wall of the well bore at a point adjacent the lower end portion of said tubular member; opening the said tubing to allow fluid to enter said tubular member from the well bore below the said packoff point; and at a location fixed with respect to said tubular member making a measure indicative of the resistivity of the mixture of all of said fluid passing said location as said fluid enters said tubular member, said measure being made in correlation with time during such entrance of such fluid into said tubular member.

6. Apparatus adapted to be lowered into a well bore for testing the production of a well comprising: a tubular member initially closed against entrance thereto of fluid from such well bore; an imperforate tubular extension of said tubular member; means for effecting a packoff between said tubular member and a portion of said well bore wall to isolate a portion of said well bore wall from other portions thereof; means intermediate said tubular member and said tubular extension to open said tubular member into communication through said tubular extension with the thus isolated portion of said well bore; and means including electrode means located within said imperforate tubular extension to make a measure of the resistivity at a fixed location therein of the whole

stream of fluids thus permitted to enter and flow through said imperforate tubular extension into said tubular member from said isolated portion.

7. Apparatus adapted to be lowered into a well bore for testing the production of a well comprising: a tubular member initially closed against entrance thereto of fluid from such well bore; an imperforate extension of said tubular member; means for effecting a packoff between said tubular member and a portion of said well bore wall to isolate a portion of said well bore wall from other portions thereof; means intermediate said tubular member and said imperforate extension to open said tubular member into communication through said imperforate extension; with the thus isolated portion of said well bore; and means including electrode means located within said imperforate extension for recording in correlation with time a measure of the resistivity at a fixed location therein of the whole stream of fluids thus permitted to enter said tubular member from said isolated portion.

8. Apparatus adapted to be lowered into a well bore for testing the production of a well comprising: a tubular member initially closed against entrance thereto of fluid from such well bore, said tubular member having an imperforate extension; packer means for effecting a packoff between said tubular member and a portion of said well bore to isolate a portion of said well bore from other portions thereof; means to open said tubular member into communication through said imperforate extension with the thus isolated portion of said well bore; and means located adjacent said packer means wholly within said imperforate extension to make a measure of the resistivity at a fixed location therein of the whole stream of fluids thus permitted to enter said tubular member from said isolated portion.

9. Apparatus adapted to be lowered into a well bore for testing the production of a well comprising: a tubular member initially closed against entrance thereto of fluid from such well bore, said tubular member having an imperforate extension; packer means for effecting a packoff of the annular space between said tubular member and the surrounding wall of the well bore at a selected location within said well bore to isolate a portion of said well bore from other portions thereof; means for opening said tubular member into communication with such isolated portion of the well bore through said imperforate extension; and means for making a measure of the resistivity at a fixed location within said imperforate extension of the whole stream of fluid thus permitted to enter said tubular member through said imperforate extension from said isolated portion.

10. Apparatus adapted to be lowered into a well bore for testing the production of a well comprising: a tubular member initially closed against entrance thereto of fluid from such well bore; packer means for effecting a packoff of the annular space between said tubular member and the surrounding wall of the well bore at a selected location within said well bore to isolate a portion of said well bore from other portions thereof; opening means for opening said tubular member into communication with such isolated portion of the well bore; and means located adjacent said packer above said opening means for recording in correlation with time a measure of the resistivity at said location of the whole stream of all of the fluid thus permitted to enter said tubular member from said isolated portion.

11. Apparatus adapted to be lowered into a well bore for testing the production of a well comprising: a tubular member initially closed against entrance thereto of fluid from such well bore; packer means for effecting a packoff of the annular space between said tubular member and the surrounding wall of the well bore at a selected location within said well bore to isolate a portion of said well bore from other portions thereof; valve means carried by said tubular member adjacent said packer means, actuatable for opening said tubular mem-

ber into communication and closing said tubular member from communication with such isolated portion of the well bore; and electrode means located within said tubular member adjacent said packer means for recording in correlation with time a measure of the electrical conductivity of all of the fluid thus permitted to enter said tubular member through said valve means from said isolated portion.

12. Apparatus adapted to be lowered into a well bore for testing fluid therein comprising: a hollow member initially closed against entrance thereinto of fluid from such well bore; valve means carried by said hollow member and actuatable for opening said hollow member into communication with fluid in said well bore; and means contained within said hollow member above said valve means for making a measure of the resistivity of all of the fluids entering said hollow member through said valve means.

13. Apparatus adapted to be lowered into a well bore comprising: a tubular member initially closed against entrance thereinto of fluid from such well bore; valve means carried by said tubular member and actuatable for opening said tubular member into communication with fluid in said well bore; and means including electrodes contained within said tubular member adjacent said valve means for making a measure of the resistivity of all of the fluids entering said tubular member through said valve means.

14. Apparatus adapted to be lowered into a well bore for testing fluid therein comprising: a tubular member initially closed against entrance thereinto of fluid from

5 such well bore; valve means carried by said tubular member and actuatable while said tubular member is located within such well bore for opening said tubular member into communication with fluid in said well bore; and means contained within said tubular member adjacent said valve means for making a measure of the resistivity of all of the fluids entering said tubular member through said valve means.

15. Apparatus adapted to be lowered into a well bore for testing fluid therein comprising: a hollow member initially closed against entrance thereinto of fluid from such well bore; an imperforate extension of said hollow member; valve means located between said hollow member and said imperforate extension and actuatable for opening said hollow member into communication through said imperforate extension with fluid in said well bore; means contained within said imperforate extension below said valve means for making a measure of the resistivity of all of the fluids entering said hollow member through said extension and said valve means.
